UNITED STATES PATENT OFFICE.

WILLIAM ERNEST BAMFORD, OF BELFAST, NORTHERN IRELAND.

MANUFACTURE OF CONFECTIONERY.

Application filed September 9, 1926, Serial No. 134,474, and in Great Britain September 17, 1925.

My invention relates to improvements in the manufacture of confectionery, and the principal object of my improvements is to provide a simple and effective device for forming the shells or casings of chocolate or other confectionery material.

The invention broadly consists in providing expansible and contractible members which can be dipped in their expanded condition into a vessel containing soft confectionery material, the members being thereafter raised clear of the vessel. A coating of confectionery material adheres to the members which are next lowered on to a support. When the confectionery has set the members are contracted and withdrawn through an opening in the hollow shells of confectionery material, leaving the shells on the support. The shells are then filled 20 with a core of suitable material and caps of confectionery material are then moulded on top, thus totally enclosing the core.

The invention is illustrated by way of example in the accompanying drawings and 25 described in the following specification and it is more particularly pointed out in the appended claims.

In the drawings examples are shown of expansible members, adapted to be expanded 30 by inflation and by mechanical means, for the manufacture of confectionery. The drawings also show examples of machines, or apparatus, for the dipping of the expanded members in the material from which the 35 shells are to be formed and, further, the drawings also show an example of a machine for capping the formed and filled shells. These machines are only shown by way of illustration.

40 Fig. 1 is a sectional elevation through a shell-forming member expanded by inflation and showing same immersed, to the required extent, in the chocolate, or other material. This view also shows how the expansible 45 member is connected with the nozzle and tube which communicates with the fluid tank from which the fluid under pressure is obtained for the inflation of the member.

Fig. 2 is a sectional elevation corresponding 50 to Fig. 1 but showing the formed shell adhering to the inflated member and showing it above a shell-supporting plate with depressions therein in which the shells can rest until they are set.

55 Fig. 3 is a section of an arrangement for the mechanical expansion of the shell-form-

ing members, the member being shown in its unexpanded condition.

Fig. 4 is a view corresponding to Fig. 3 but showing the expansible member mechanically expanded. It will be observed that the shell forming member in Figs. 3 and 4 is different in shape to that shown in Figs. 1 and 2.

Fig. 5 is an elevation of a portion of a reversible support carrying a capping tray or mould and showing the tray in position for filling.

Fig. 6 is an elevation corresponding to Fig. 5 but showing the tray reversed and ready 70 for the capping operation.

Fig. 7 is a sectional elevation of the confection shell filled with any desired filling material and resting on the supporting plate.

Fig. 8 is a sectional elevation of the completed confection, capped and ready to be removed from the supporting tray by tapping, or otherwise. The supporting tray would, in the case of fondants and like goods, 75 preferably be in the form of a rubber mat 80 mould. Any desired design could be embossed on the plate or mat for reproduction on the shell.

Fig. 9 shows in side elevation an example of a machine for the dipping of the inflated 85 members.

Fig. 10 is an end elevation of the machine shown at Fig. 9.

Fig. 11 is a plan view of a plate for supporting the formed shells and showing rails 90 on which it may be moved into and out of working position.

Fig. 12 shows in sectional elevation on line 12—12 of Fig. 13 an example of a capping machine such as could be used in connection with the invention.

Fig. 13 is an end elevation of the capping machine shown at Fig. 12.

Fig. 14 is a sectional plan view on line 14—14 of Fig. 12 showing the reversible 100 members, or carriers for the capping trays.

Figs. 15 and 16 are views corresponding to Figs. 9 and 10 of a modified construction showing expansion controlling means in position.

Fig. 17 is a detail view of one of a plurality of valves.

Fig. 18 is a detail view showing a modified construction of expansion controlling means.

Referring to the drawings:—
1 is the tube leading from the pressure fluid supply tank 2 (see Fig. 9) and having at

its end a nozzle 1^a upon which the member 3, adapted for expansion by inflation, is supported. In the example shown the member 3 has an internal shoulder 3^a which fits into a corresponding groove on the nozzle whereby all the members 3 can be correctly positioned on the nozzles which latter can be properly levelled, by adjustment relatively to the tube 1, thereby ensuring equality of depth in the dipping of the members 3 into the chocolate, or other confectionery material 4. The contracted shape of the member 3 is shown by the dotted lines 3^b. The member 3 is also held securely in position by suitable tying or other means and by means of a cylindrical member or sleeve 5, adjustably secured to the nozzle 1^a and having a tapered end 5^a to suit the shape of a flange 3^c which is provided on the member 3 and adapted to regulate the size of the opening in the shell 6 (see Fig. 2) formed on the outside of the member 3. The flange 3^c is made with a slightly tapered portion where it leaves the member 3 and terminates in a vertical portion. The uprising flange 3^c ensures the formation of substantially uniform openings in the shells should the members 3 be dipped to depths greater than normal.

Fig. 2 shows the member 3 withdrawn from the chocolate 4 and showing the chocolate shell 6 formed thereon, the nozzle and member 3 and the shell 6 being shown about to be lowered on to the supporting plate 7, slideable on runners 7^b and shaped with depressions 7^a therein.

Instead of the member 3, as shown at Figs. 1 and 2, an expansible member 8 may be provided which is adapted to be expanded mechanically. Such an arrangement is shown at Figs. 3 and 4, Fig. 3 showing a member 8 unexpanded and Fig. 4 showing a member 8 expanded. In the example shown expansion of each member 8 is obtained by means of a rod 9, to which is attached two grooved and slotted discs 10 and 11 to which, in turn, are attached any required number of ribs 12 and 12^a respectively, which are led through slots 13^a in an outer tube 13 and are connected at their outer ends to stretchers 14, bearing on the inner surface of the member 8. The tube 13 is lengthwise adjustable, by means of a turnbuckle 13', so that the member 8 may be properly levelled, and the length of the rod 9 may be adjusted by screwing it more or less through a supporting plate 15 or by means of a turnbuckle 9'. The lower ribs 12^a are curved as shown to give horizontal expansion of the stretchers 14 by bearing on the bottom of the slots 13^a so that as the rod 9 is lowered, the ribs 12^a will force out the stretchers 14 to the position shown at Fig. 4. Any means may be employed to raise and lower the rod 9 relatively to the tube 13. For illustration purposes only, the rod 9 is shown attached to the plate 15 and the tube

13 is shown attached to a plate 16. The thumbscrew nut 17 (which may be one of a pair of such nuts, one at each end of the plate 15) is turned to raise or lower the plate 15 relatively to the plate 16 and so produce the required inward or outward movements of the stretchers 14. The outward movement of the stretchers 14 causes expansion of the member 8 as shown at Fig. 4 which is then the equivalent of the inflated member 3 shown at Fig. 1 and the subsequent operation is exactly the same as described with reference to Fig. 1. Any suitable number of stretchers 14 may be employed and attached to the required number of ribs 12 and 12^a. By increasing or decreasing the number of stretchers the shape of the member 8 can be controlled and the shape can be further or alternatively controlled by suitable shaping of the stretchers 14 and also by suitable positioning of the stretchers 14 so that a square, hexagonal, cylindrical or other shape can be readily obtained as desired.

The expansible members 3 or 8, shown at Figs. 1 or 3 could be operated for dipping by a machine such as illustrated at Figs. 9 and 10. The machine shown comprises a pan, or tank, 4^a of confection 4 which is preferably automatically heated to the proper temperature for dipping the expansible members thereinto. The members 3, connected by their tubes 1 with the tank 2 are supplied with fluid under pressure from the tank 2, which tank has two valves 2^a and 2^b one of which is the inlet valve and the other the outlet valve, fluid under pressure being admitted by say the valve 2^a whilst the valve 2^b is an exhaust valve to which, if necessary, an exhaust pump can be attached for the deflation of the members 3. The members 3 are lowered and raised into and out of the confectionery material 4 through the medium of racks 18 and pinions 19 on a shaft 19^a driven by any suitable means. When the members 3 have been dipped and raised with the confection material thereon to form the shells, the plate 7 is then pushed into position below the members 3 which are lowered until the formed shells rest in the hollows 7^a of the plate 7 where they are allowed to set. When the shells are set the members 3 are deflated and withdrawn leaving the shells resting on the plates 7 as shown at Fig. 7. They can then be filled with filling material 6^a in any usual manner and they may be capped by providing suitable capping trays 20 which, in the example shown, are supported on reversible supports 21. The capping material is filled into the trays 20 as shown at Fig. 5 and when the material is almost set the supports 21 are reversed as shown at Fig. 6 and the apparatus lowered until the caps fit over the openings 6^b in the confections 6.

An arrangement or example of a capping

machine is shown at Figs. 12 to 14. The capping trays 20 are attached to the reversible supports 21 by means of studs 29 slideable in the supports, compression springs 29' embracing the studs being interposed between the trays and supports which, in turn, are attached to a frame 22 adapted to be raised and lowered. The raising and lowering of the frame 22 is shown to be performable by means of racks 23 and pinions 24, but of course any other suitable raising and lowering means could be used. The turning of the supports 21 is shown as capable of being effected by bevel pinions 25 on a shaft 26 with an operating handle 26a, the pinions 25 meshing with similar pinions 27 on shafts 28 secured to the support 21. The shells 6 on the plate 7 are shown at Figs. 12 and 13 in position ready for the capping operation.

20 The plan view at Fig. 14 is taken just immediately above the reversible supports 21.

The general description of the operation has been described with reference to the members 3, but the operation and procedure 25 is generally the same for the mechanically expanded members 8.

After the formed, filled and capped shells are completed and set they can be readily released from the plates 7 and cap moulds 30 by tapping the plate and cap supports. The releasing of the confections from mat moulds would be effected by suitable movement of the mats.

In the case of the inflatable members 3 35 pressure may, if desired, be applied individually to the members 3 in order to ensure equal expansion thereof.

When the members 3 are inflated they may be expanded to different sizes owing to uneven distribution of fluid during inflation. 40 Means may be provided by which the size can be controlled, such means comprising a control valve for each member and a plurality of gauges for limiting the extent of expansion of the members.

As shown in Figs. 15 and 16, a plate 30 can be slid along the runners 7^a into a position beneath the members 3 in which the latter can be lowered into register with cup-shaped cavities 31, constituting gauges, in the plate 30. A valve 32 is interposed between each tube 1 and the tank 2 and is provided with an operating lever 33 which passes through one of a series of slots 34 in one of a number of connecting rods 35. The rods 35 are interconnected by transverse rods 36. By means of the handle 37 on one or more of the rods 35, the valves may be operated simultaneously.

Instead of the cavities 31, the gauges may 60 be presented by cups 38 which are adjustably screwed into the plate 30.

In operation, the gauges are moved into position below the expandable members 3, which are lowered the requisite amount. 65 Thereafter, the valves 32 are opened and the

members inflated. When all the members have expanded to the limit determined by the gauges and the pressure of the fluid has become stabilized throughout the system, the valves are closed and the gauges are withdrawn. 70

What I do claim as my invention and desire to secure by Letters Patent is:—

1. A device for the manufacture of confectionery comprising an expandable and contractible member, means whereby said member may be expanded and contracted, means for controlling the size to which the said member may be expanded, a vessel adapted to contain soft confectionery material and mechanism for moving the expandable member into and out of said vessel. 75

2. A device for the manufacture of confectionery comprising an expandable and contractible member, means whereby said member may be expanded or contracted, means for controlling the size to which said member may be expanded or contracted, means for coating the member with confectionery material, a movable support for receiving the confectionery material and mechanism for lowering and raising the said expandable member toward and away from said support. 85

3. A device for the manufacture of confectionery comprising an expandable and contractible member, means whereby said member may be expanded or contracted, means for controlling the size to which said members can be expanded or contracted, a vessel adapted to contain soft confectionery material, a support for said confectionery material and mechanism for moving the said member, with confectionery material adhering thereto, on to said support and for moving the said member so as to leave the confectionery material on said support. 90

4. A device for the manufacture of confectionery comprising a plurality of expandable and contractible members, means whereby said members may be expanded or contracted, means for controlling the size to which said members can be expanded or contracted, means for coating said members with confectionery material, a support formed with depressions for reception of the confectionery material coated on said members, and mechanism for moving said members in unison so as to leave the confectionery material on said support. 105

5. A device for the manufacture of confectionery comprising a plurality of expandable and contractible members, means whereby said members may be expanded or contracted, means for controlling the size to which said members can be expanded or contracted, and mechanism for raising and lowering said members in unison. 110

6. A device for the manufacture of confectionery comprising a plurality of expandable and contractible members, means whereby 115

- said members may be expanded or contracted, means for controlling the size to which said members can be expanded or contracted, mechanism for raising and lowering said members in unison and means for adjusting the heights of individual expansible and contractible members relatively to each other.
7. A device for the manufacture of confectionery comprising an expansible and contractible member, means whereby said member may be expanded and contracted, a vessel adapted to contain soft confectionery material, mechanism for lowering said member into said confectionery material and for raising the said member, with a coating of confectionery material adhering thereto, clear of said vessel and an uprising flange on said member adapted to form an opening in said adhering confectionery material.
8. In a device for manufacturing confectionery, a pressure fluid container, a tube leading from said container, a nozzle on said tube, an inflatable and deflatable member jointed to said nozzle, means for controlling the admission and withdrawal of pressure fluid from said container and mechanism for raising and lowering the said elements.
9. In a device for manufacturing confectionery, a pressure fluid supply, a plurality of inflatable and deflatable members connected with said supply, devices for controlling the admission and withdrawal of pressure fluid to and from the individual members, and means for operating the said controlling devices simultaneously.
10. A device for manufacturing confectionery, comprising a plurality of inflatable and deflatable members, a corresponding plurality of gauges for said members, means whereby said members can be inflated to the size permitted by said gauges, means for stopping the inflation of said members and mechanism for moving the said members into register with the said gauges and for moving the said members, when inflated clear of the said gauges.
11. A device for manufacturing confectionery, comprising a plurality of inflatable and deflatable members, a corresponding plurality of cup-shaped gauges for said members, means for adjusting the heights of individual gauges relatively to each other, means whereby said members can be inflated to the size permitted by said gauges, means for stopping the inflation of said members and mechanism for moving the said members into register with the said gauges and for moving the said members, when inflated clear of the said gauges.
12. A device for the manufacture of confectionery, comprising an expansible and contractible member, means for coating said member with confectionery material, an uprising flange on said member adapted to form a hole in said confectionery, a support for said material, means for withdrawing said member from said material by way of said hole and means for closing said hole with confectionery material.
13. A device for the manufacture of confectionery comprising an expansible and contractible member, means for coating said member with confectionery material, an uprising flange on said member adapted to form a hole in said confectionery, a support for said material, means for withdrawing said member from said material by way of said hole, reversible moulds adapted to contain soft confectionery material and means for reversing said moulds, when the said last-mentioned material is almost set, and for applying the said material to the said hole to close it.
14. A device for the manufacture of shells of confectionery material, comprising an expansible and contractible member having an uprising flange, and means whereby said member may be expanded to form a mould for a shell and contracted to permit it to be removed through an opening formed by said flange in the shell.
15. A device for the manufacture of shells of confectionery material, comprising an expansible and contractible member having an uprising flange, a vessel adapted to contain soft confectionery material, mechanism for lowering the member into said vessel to the level of said flange and withdrawing the member therefrom.
16. A device for the manufacture of confectionery, comprising an expansible and contractible member with an uprising flange, means whereby said member may be expanded and contracted, means for controlling the size to which the said member can be expanded, a vessel adapted to contain soft confectionery material, and mechanism adapted to dip the expansible member to the level of the said flange into said material and to withdraw it therefrom.
17. A device for manufacturing confectionery, comprising an expansible and contractible member adapted to form a mould for the confectionery, an uprising flange on said member, means whereby said member may be expanded, means for coating said member with confectionery material up to the level of said flange, and means whereby said member may be contracted to permit of its removal from the confectionery by way of an opening formed in the confectionery by said flange.
18. A device for manufacturing confectionery, comprising a plurality of expansible and contractible members adapted to form a mould for the confectionery, an uprising flange on each of said members, means for expanding said members, a vessel adapted to contain confectionery material, means for dipping said members into the vessel to coat

them with confectionery material up to the level of the flanges, means for contracting said members to permit of their removal from the confectionery by way of openings

5 formed by the flanges, and a support for receiving the confectionery so formed.

19. A device for manufacturing confectionery, comprising a plurality of expandible and contractible members adapted to form a

10 mould for the confectionery, an uprising flange on each of the members, means for expanding and contracting said members, a vessel adapted to contain confectionery material, a support for receiving the confectionery 15 when moulded on the members, and means for successively moving the said members into and out of said vessel, on to said support and away from said support.

20. In a device for manufacturing confectionery, a pressure fluid supply, a tube leading from said supply, an inflatable and deflatable member attached to said tube, an uprising flange on said member, means for admitting and withdrawing pressure fluid from 25 said member, a vessel adapted to contain soft confectionery material, and mechanism for dipping said member into said material to the level of said flange and for withdrawing said member from the material.

30 21. A device for manufacturing confectionery, comprising a plurality of expandible and contractible members formed with uprising flanges and adapted to form a mould for the confectionery, means for expanding 35 said members, a vessel adapted to contain confectionery material, means for dipping

said members into the vessel to coat them with confectionery material up to the level of the said flanges, means for contracting said members to permit the removal of the confectionery formed thereon by way of holes formed by the flanges, a support for receiving the confectionery so formed, and means for applying caps to the confectionery.

40 22. A device for manufacturing confectionery, comprising a pressure fluid container, a tube leading from said container, a nozzle on said tube, an adjustable sleeve on said nozzle, an inflatable and deflatable member supported on said adjustable sleeve, means 50 for controlling the admission and withdrawal of pressure fluid from the inflatable and deflatable member, and means for raising and lowering the said elements.

45 23. A device for manufacturing confectionery, comprising a pressure fluid container, a tube leading from said container, a nozzle on said tube, an adjustable sleeve on said nozzle, an inflatable and deflatable member with an uprising flange cooperating with the 55 adjustable sleeve to control the opening formed in confectionery made by dipping the inflated member in prepared material, means for lowering said inflated member into the confectionery material, and means for raising 60 the said inflated member out of the confectionery material and for deflating the said inflated member and for withdrawing same by way of said hole from the said material.

65 In testimony whereof I affix my signature.

WILLIAM ERNEST BAMFORD.
